United States Patent Office

Des. 184,464
Patented Feb. 17, 1959

184,464

PLATE OR SIMILAR ARTICLE

Gerald S. Stone, Scarsdale, N. Y., assignor to Johnson Bros. (Hanley) Limited, Hanley, England, a British company

Application September 9, 1958, Serial No. 52,571

Term of patent 14 years

(Cl. D44—15)

A top plan view of a plate or similar article of conventional configuration illustrates my new design.

I claim:

The ornamental design for plate or similar article, substantially as shown and described.
